UNITED STATES PATENT OFFICE.

KOSCIUSKO M. ANDERSON, OF LOMETA, TEXAS.

GATHERING MACHINE.

Application filed October 5, 1925. Serial No. 60,426.

This invention relates to new and useful improvements in gathering machines, and especially has to do with cotton, maize, etc., after being picked by hand.

5 The object of the invention is to provide an apparatus to be drawn along rows of crops by any suitable means, and whereby the workman may either ride or walk along and pick the crop, placing the same in the 10 apparatus which conveys it into a receptacle provided therefor.

Another object of the invention is to incorporate in the apparatus, a receptacle for containing the picked crop and to be suspended 15 from a weighing mechanism whereby the quantity is ascertained by weight.

A further object of the invention is to provide means for horizontally adjusting the apparatus to various widths of rows and 20 also means for vertically adjusting the same for plants of different heights.

A still further object of the invention is to provide an apparatus of the character described having self-driving means for the 25 different parts, which will actuate as it is propelled along the rows.

A construction designed to carry out the invention will be hereinafter described together with other features of the invention.

30 The invention will be more readily understood from a reading of the following specification and by reference to the accompanying drawings, in which an example of the invention is shown, and wherein:

35 Fig. 1 is a front elevation of a gathering machine constructed in accordance with my invention,

Fig. 2 is a side elevation of the same,

40 Fig. 3 is an enlarged vertical sectional view taken on the line 3—3 of Fig. 1,

Fig. 4 is an enlarged detail showing the vertical axle adjusting means,

Fig. 5 is an enlarged sectional view of the axle parts,

45 Fig. 6 is a detail of the take-up of the driving mechanism,

Fig. 7 is an enlarged cross section taken on the line 7—7 of Fig. 5,

Fig. 8 is a cross section taken on the line 50 8—8 of Fig. 1,

Fig. 9 is a sectional view taken on the line 9—9 of Fig. 3,

Fig. 10 is a plan view of a portion of the conveyor belt, and

55 Fig. 11 is an underside detail of the conveyor frame mounting.

In the drawings the numeral 10 designates the receptacle frame having reach bars 11 extending forwardly and reach bars 12 extending downwardly across to a transverse beam 13 to which they are fastened. The bars are spaced apart and form supports for a middle conveyor frame 14. Draft bars 15 extend forwardly from the beam 13 and the front ends carried by a front or guide wheel 16. Suitable seats 17 are provided on the bars for the workmen and may be adjusted either vertically or horizontally as may be desired. However it is to be understood that the seats are not a necessary part of the invention which may be used with or without same.

End conveyor frames 18 may be moved inward or outward as shown in dotted lines (Fig. 1) thus providing horizontal adjustment for different width rows. The frames are supported at their lower portion by means of slideable bearings 19 on a bar 20 which is fastened to the beam 13 by means of brackets 21. The upper portions of the conveyor frames are similarly fastened by means of bearings 22 on a slide bar 23 mounted on the frame 10 by brackets 23'. The middle conveyor is considerably wider than the end conveyors as more capacity is necessary when both sides of the apparatus are being worked simultaneously.

At the upper ends of the conveyor frames is journaled a transverse shaft 24 on which is mounted drums 25. An endless conveyor belt 26 has its upper end supported on the drum 25 while its lower end is supported by a smaller drum 27 on a short shaft 27' which is journaled in a hopper 28 which is formed integral with the conveyor frame. The belt 26 may be made of any suitable material and has a plurality of right angular strips 28' which have upwardly directed teeth 29. These teeth are provided for holding the crops more securely when they are picked and thrown onto the conveyor. An idler 30 is provided underneath the conveyor frame to take up any slack in the conveyor belt.

A receptacle 31 is suspended in the frame 10 by means of any suitable weighing mechanism. I have shown a scale beam 32 in the drawings. The beam has a hook 32' which is engaged in an eye bolt 33. The bolt passes through a cross beam 34 which is supported by means of standards 35 fastened to the frame 10. Another hook 32' is engaged with a suspension frame 31'

which is fastened to the receptacle. A weight 32^b is placed on the beam 32 and may be moved along to equalize the balance. A door 36 is provided in the rear side of 5 the receptacle for emptying the same.

For the raising or lowering of the machine in accordance with the height of the crop being picked and also to get a horizontal adjustment of the ground wheels according 10 to the width of the furrows, a novel construction of the axle is devised in which a transverse hollow axle 37 is rotatably confined and held against longitudinal displacement in bearing boxes, 44, secured to 15 the underside of the frame 10. A crank axle 38 is mounted in each end of the axle 37 and supported in the hub 39 of ground wheels 39.

For horizontal adjustment of the wheels 20 a key 41 is riveted in an internal groove 42 in the axle 37 and received in a corresponding groove 43 in the crank axle 38. It will be readily seen that by this arrangement the crank axle cannot rotate without 25 the axle 37. However it may be moved in or out as shown in dotted lines (Figs. 1 and 5).

For vertical adjustment of the apparatus hand levers 40 are riveted to the axle 37 30 and extend vertically (normal position) on each side of the frame 10. By pulling the lever forwardly as is shown in dotted lines (Fig. 4) the axle 37 will turn causing the crank axle to do likewise. As the crank 35 axle is offset from the end mounted in the axle 37 and the hub portion, it is obvious that by traveling on an arc greater than the circumference of the axle the entire apparatus will raise. The desired height may 40 be maintained by releasing the pivoted hand grip 45 which is under the tension of the spring 46. As this is done the plunger 47 will engage with one of the teeth 48, of the locking segment 49 which is mounted to the 45 side of the frame 10.

For driving the various parts a sprocket 50 is made integral with the hub 39 of the ground wheel. The sprocket drives an endless chain 51 having its upper end passing 50 around a smaller sprocket 52. This sprocket is made integral with a gear 53 meshing with another gear 54 mounted on the shaft 24.

It will be seen that as the machine is 55 drawn along, the ground wheels 39' will cause the chain 51 to travel and drive the gears thereby causing the conveyor to move in a counter-wise direction to the ground wheels.

60 To compensate for the various positions and locations of the sprocket 52 due to the vertical adjustment means the sprocket is mounted on an arm 55 whose end is fastened on the shaft 24. The opposite end 65 of the arm is bent downward and has a

coiled spring 56 fastened to it at one end and to an upright post 57 at the other. The travel of the sprocket 52 will be on the same arc to the shaft 24 as the sprocket 50 will be to the axle. It is obvious by this arrangement as the spring 56 holds the chain taut there will be equal distance and tension on the chain regardless of the positions of the different parts. 70

In using the apparatus the desired height 75 is obtained by adjusting the lever 40 which places the apparatus in condition for the particular height of the crop. The width of the rows is then ascertained and the crank axles pulled out accordingly. The 80 apparatus is attached to suitable power such as animal or tractor and drawn along the rows of crops. As the apparatus is moved along the drums 25 will be put into action 85 thereby causing the conveyors to carry the crops upwardly and discharged into the receptacle as they are picked and thrown onto the conveyor belt. It is obvious that the workman may either ride or walk while 90 the crops are being picked. 95

As the crops are discharged into the receptacle they may be weighed at any time or may have a predetermined set weight which will register when the particular weight has been reached. It is to be understood that various changes and modifications as well as alterations may be made in the driving connection and the arrangement of the different parts as described and illustrated, within the scope of the appended 100 claims.

What I claim is:

1. In a gathering machine, a portable frame, a plurality of vertically inclined spaced elevating conveyors mounted upon a fixed support on the frame, means for adjusting said conveyors laterally and relatively to each other upon said support, and a container disposed at the delivery from 105 said conveyors. 110

2. In a gathering machine, a portable frame, a support projected forwardly therefrom and carrying a cross bar, a plurality of conveyor frames slidably mounted for horizontal adjustment upon said bar and provided with a hopper at their lower ends, endless belts mounted to travel within the conveyors, and a container disposed at the 115 delivery from said belts. 120

3. In a gathering machine, a portable frame, a support projected forwardly therefrom and carrying a cross bar, a plurality of conveyor frames slidably mounted for horizontal adjustment upon said bar and provided with a hopper at their lower ends, endless belts mounted to travel within the conveyors, a bar carried by the upper portion of the portable frame, a plate intermediate the belt reaches, a bearing on said 125 plate horizontally adjustable on the frame 130

bar, and a container disposed at the delivery from said belts.

4. In a gathering machine, a portable frame, a support projected forwardly therefrom, a plurality of vertically inclined spaced conveyors mounted upon the frame and support, means for adjusting said conveyors laterally and relatively to each other upon said support, a container disposed at the delivery from said conveyors, means for driving said conveyor, ground wheels for the portable frame having means for elevating the frame thereon, and a power connection for maintaining a constant driving connection between the conveyor and wheels.

5. In a gathering machine, a portable frame, a hopper carried at the front thereof, a vertically inclined conveyor extending from the hopper, a container below the upper end of the conveyor and provided with a discharging closure, and a weighing device supported by the frame above said container and from which the container is suspended free from contact with the frame.

6. In a gathering machine, a frame, ground wheel hubs having sprockets secured thereon, means for adjusting said wheels relative to the frame, an endless chain extending from said sprocket, a conveyor having a driving

shaft and gear, a sprocket wheel and gear 30 meshing with the drive shaft gear, an arm pivoted on said shaft and supporting said sprocket and gear, and a tension spring for elevating said arm.

7. In a gathering machine, a portable frame, a vertically inclined conveyor mounted thereon, axles and wheel supporting said frame and adjustable laterally thereof, a hopper at the lower portion of said conveyor, a front arch beam carrying a guide wheel support, a drive shaft journalled in the upper portion of the frame for said conveyor, a sprocket adjustable horizontally on said shaft, a sprocket upon one of said adjustable axles and having a 40 chain connection with the first mentioned sprocket, and a container disposed at the delivery from the conveyor.

8. In a gathering machine, a portable frame, a plurality of elevator conveyors 50 having slidable bearings secured to the underside thereof, bars mounted on the frame and a beam upon which the bearings slide, and brackets securing said bars to the frame and beam.

In testimony whereof I affix my signature.

KOSCIUSKO M. ANDERSON.
